UNITED STATES PATENT OFFICE.

EDWIN GAUTHIER, OF MATTOON, WISCONSIN.

STONE-PULLER.

1,266,674.

Specification of Letters Patent.

Patented May 21, 1918.

Application filed August 29, 1917. Serial No. 188,753.

To all whom it may concern:

Be it known that I, EDWIN GAUTHIER, a citizen of the United States, and resident of Mattoon, in the county of Shawano and 5 State of Wisconsin, have invented new and useful Improvements in Stone-Pullers, of which the following is a description, reference being had to the accompanying drawings, which are a part of this specification.

10 The invention relates to stone pullers.

The invention is designed to provide a device which will readily loosen a stone from its bed, lift the stone up on its own carriage so that it may be easily carried away and is 15 especially useful in clearing land for agricultural purposes.

The invention further consists in the several features hereinafter set forth and more particularly defined by claims at the conclusion hereof.

In the drawings:

Figure 1 is a side view of the device embodying the invention in full lines showing it in position for removing a stone and in 25 dotted lines showing the stone removed and ready to be carried away;

Fig. 2 is a plan view of the device;

Fig. 3 is a detail view of a modified form of one of the parts of the device, parts being 30 broken away.

In general the device comprises a carriage 4 and a stone clamping mechanism carried thereby and coöperating therewith to lift the stone from its bed and carry it 35 away.

The carriage consists of a sled having runners 5, metal frame members 6 secured to the runners, transverse frame members 7 secured to the members 6 and to the runners, 40 braces 8 secured to the members 7, stone lifting members 9 secured to the members 7 and joined together at their front ends, and a draw bar 10 secured to the members 9.

The stone clamping mechanism consists of 45 the members 9 and a clamping and lifting member 11 pivotally secured at a distance from the carriage to upwardly extending supports 12 and 13.

The members 9 have upwardly curved 50 ends 14 and intermediate curved portions 15 forming with the carriage a basket for receiving the rock.

The member 11 is pivotally secured at one end 16 to the supports 12 and 13 and is 55 arcuate-shaped to form an inwardly curved pointed end 17 which is provided with teeth

18. The member 11 is also provided with a projection 19 near the end 17 so that the end 17 may be driven into the ground beside the rock by a sledge or other suitable means. 60

After the rock has been lifted from the soil it is secured to the sled by a chain 20 which is detachably secured at its ends to eyebolts 21 on the runners 5.

In Fig. 3 a portion of a modified form of 65 clamping member 11' has been shown in which the lower end 17' is bifurcated.

With this construction when it is desired to remove a rock the device is placed upright beside the rock so that the ends 14 of 70 the members 9 are embedded in the soil and rest against the rock and so that the ends of the runners are upright and rest upon the ground or are partially embedded in the soil. The clamping member 11 is then 75 swung down over the rock and its end 17 or 17' driven into the ground beside the rock on the opposite side from the members 9. The device is now ready for pulling the rock which is accomplished by applying power 80 to the draw bar 10, a team of horses or other suitable source of power being connected up to said bar to pull the sled over upon the ground. In pulling the sled, the ends of the runners act as a fulcrum, the members 9 85 act as a pry and the member 11 serves to lift and hold the rock to the carriage as it is being pulled up and tipped over onto the carriage. When pulled over, the device assumes the dotted line position of Fig. 1, the 90 chain 20 is brought over the rock to secure it upon the sled and the team draws the sled away to the place where the rock is to be disposed of.

The invention thus exemplifies a simple 95 and efficient device for extracting and carrying away stones from farm land.

I claim:

1. In a stone puller, the combination of a carriage, a lifting member fixedly carried thereby and provided with outwardly projecting spaced apart ends for engaging the rock, a clamping and lifting member pivotally secured to the forward portion of the carriage and coöperating with said lifting member to lift the rock from its bed onto the body of the carriage, and means at the forward end of the carriage for applying power thereto. 105

2. In a stone puller, the combination of a 110 sled, lifting members mounted on said sled and having outwardly extending ends pro-

jecting therefrom, a clamping and lifting member pivotally secured to the forward portion of the sled and coöperating with said lifting members to lift the rock from its bed onto the body of the sled, and means at the forward end of the sled for applying power thereto.

3. In a stone puller, the combination of a sled, lifting members mounted thereon and having outwardly extending ends projecting from the rear end of the sled, supports extending upwardly from the forward portion of the sled, a clamping and lifting member pivotally secured to said supports at a distance from the sled and coöperating with said lifting members on the sled, and a draw bar at the forward end of the sled for applying power thereto.

4. In a stone puller, the combination of a sled, lifting members fixedly mounted thereon and having outwardly extending ends projecting from the rear end of the sled, a curved clamping and lifting member pivotally secured to the forward portion of the sled and coöperating with said lifting members to lift the rock on the sled, said clamping and lifting member having a toothed end, and means at the forward end of the sled for applying power thereto.

5. In a stone puller, the combination of a carriage including runners, lifting members mounted on the carriage and having outwardly extending ends projecting from the rear end thereof, supports extending up-

wardly from the carriage, a curved clamping and lifting member pivotally secured to said supports at their upper portions and coöperating with said lifting members on the carriage, said clamping and lifting member having a toothed end and a projection for facilitating driving into the soil, and a draw bar at the forward end of the sled for applying power thereto.

6. In a stone puller, the combination of a sled provided with runners having pointed rear ends to embed in the ground, spaced apart lifting members carried by the sled and having their rear ends projecting outwardly from the rear ends of the runners to engage the rock, and a clamping and lifting member pivotally secured to the sled and coöperating with said lifting members to lift the rock from its bed when said sled is moved from upright to horizontal position.

7. In a stone puller, the combination of a carriage, lifting members mounted on the carriage and having outwardly extending ends projecting from the rear of said carriage, a curved clamping and lifting member pivotally secured to said carriage and coöperating with the lifting members on the carriage, said clamping and lifting member having a projection for facilitating driving into the soil, and means for applying power to the front end of the carriage.

In testimony whereof I affix my signature:
EDWIN GAUTHIER.
